UNITED STATES PATENT OFFICE

150,933

DESIGN FOR A HOUSING FOR A SPACE HEATER

Harry J. Clark, Monrovia, Calif.

Application March 1, 1947, Serial No. 137,258

Term of patent 3½ years

(Cl. D81—19)

To all whom it may concern:

I, Harry J. Clark, a citizen of the United States, residing at Monrovia, county of Los Angeles, State of California, have invented a new, original, and ornamental Design for a Housing for a Space Heater, of which the following is a specification, reference being had to the accompanying drawing, constituting a part thereof.

Fig. 1 is a side elevation of a housing for a space heater, showing my new design; and

Fig. 2 is a perspective view thereof.

The dominant features of my design reside in the portion shown in full lines.

I claim:

The ornamental design for a housing for a space heater, substantially as shown and described.

HARRY J. CLARK.
